DEWATERING AND CLASSIFYING
CONVEYER

Raymond W. Dull, La Grange, Ill.

Application February 10, 1940, Serial No. 318,313

13 Claims. (Cl. 209—463)

My invention relates to improvements in de-watering and classifying conveyers and has for one object to provide a new and improved apparatus for de-watering sand, gravel, coal and the like.

Another object is to provide such means as will operate effectively and continuously to avoid the necessity of reciprocating or intermittently operating mechanism, and to provide means in connection with such apparatus for lubricating the supporting and moving parts, and to provide means for increasing the life of the apparatus.

My invention is illustrated more or less diagrammatically in the accompanying drawings, wherein:

Figure 1 is a longitudinal section with the drive end shown in side elevation.

Figure 2 is a plan view of the device shown in Figure 1.

Figure 3 is a section along the line 3—3 of Figure 1.

Figure 4 is a detail longitudinal section of a modified form of my device.

Figure 5 is a section along the line 5—5 of Figure 4.

Figure 6 is a section along the line 6—6 of Figure 4.

Figure 7 is a diagrammatic view of a treatment system making use of my device.

Figure 8 is a diagrammatic section through a modified form of my device.

Like parts are indicated by like characters in the various drawings.

1 is a supporting frame from which extend upwardly columns 2, 3, supporting a trough of rectangular cross sectional area, having side walls 4, 5, a feed floor 6, and a discharge floor 7, the feed floor being more sharply inclined to the horizontal than the discharge. 8—8 are a series of wearing strips extending throughout the length of the trough from feed to discharge end and projecting slightly above floors 6 and 7 and removably mounted thereon. 9—9 are a series of water or liquid supply pipes discharging inwardly and upwardly through the discharge floor of the tank, and receiving water under pressure through the pipes 10 from any suitable source of supply, such as pump 11.

12 is an endless belt adapted to rest upon and travel along the wearing strips 8. This belt travels over the belt driving pulleys 13, 14, supported on the frame 15, and the idler pulley 16 between the pulleys 13 and 14, the pulleys 13 and 14 are driven by drive chains 17 traveling over drive pulleys 18 and driving pulleys 19 as indi-

cated, being driven by any suitable source of power. The pulley 14 is tangent to the floor 6 so that as the belt 12 leaves the pulley 14 it is discharged along a line in prolongation of the floor 6.

21 is an idler and discharge pulley tangent to the floor 7, mounted on a supporting frame 22. 23 is an intermediate idler and guide pulley. As the drive pulleys 13 and 14 are rotated they exert a tension on the belt propelling it in the direction of the arrows around the pulleys 23 and 21 and discharging it into the trough. The water which is fed in through the pipes 9 flows out as indicated by the arrows in Figure 3 around the edges of the belt which terminates short of the walls of the trough, lubricating the belt, the belt being preferably of rubber, which lends itself especially to lubrication by water, the spaces between the belt, the floor and the wearing strips 8 providing adequate passage for the water, whereby it reaches every part of the under side of the belt. The continuous flow of water also prevents the entrance of sand, grit, etc., into the space beneath the belt.

25 25 is a feed spout, through which sand, or sand and gravel, or coal, or any other material which it is desired to de-water may be discharged. This material engages and travels upon the inclined guide plate 26, and the inclined skirt boards 30 27, and 28. The guide plate 26 is generally keystone shaped. The skirt boards and the walls 4 and 5 are cut away to form spillways at 29 and because of the inclination of the skirt boards 27 and 28 and the inclination of the floor 7, the space 35 between the skirt boards gradually expands in the direction of the travel of the belt.

As the material is deposited continuously on the central or adjacent the central axis of the belt, and as that material is propelled through the body of water by the belt, it tends to spread out, being resisted only by the resistance to flow and by the inward trend of water travelling in the direction of the arrows shown in Figures 3 and 6. This would result in jamming against 45 the skirt boards and this jamming is prevented by the gradual expansion of the space between them as above referred to.

The material discharged into the trough is concentrated and guided by the guide plate and 50 the skirt boards and discharged against the central portion of the belt so that as the belt is drawn through the water, which fills the trough, the material is distributed upon the belt, and travels upwardly with the belt above the liquid level 30 and along the discharge floor to beulti-

mately discharged from apparatus over the pulley 21. The smooth, continuous travel of the belt with its overburden insures the minimum of agitation and results in a smooth, continuous withdrawal and separation from the water of the material carried by the belt.

In the modified form, shown in Figures 4, 5, and 6, there is substituted for the skirt boards, 27 and 28, and guide plate 26, a classifier tank 35. The material to be de-watered is fed to the tank by the feed chute or spout 36. The excess water is discharged through the chute 37. The adjusting screws 38 and hand wheels 39 associated with the columns 40 and the framework 41 make it possible to adjust the classifier tank in the de-watering tank so as to adjust the spaces between the two tanks.

42—42 are fixed guide boards extending upwardly and outwardly from the trough from immediately above the belt 12, to discharge through the spillway 43. The floor of the classifier tank 35 is formed of two inclined plates 44, generally parallel with the plates 42 so that when the classifier tank 35 is raised or lowered with respect to the de-watering tank the width of the sorting column between plates 42 and 44 is increased or decreased thereby limiting the size of the particles of the sorting column.

45 is an angular discharge valve in the bottom of the classifier tank adjustable toward and from the lower edges of the plates 44 by the pull rod 46 and controlled by the hand wheel 47. The water or liquid runs out around this valve 45 into the sorting column. The water level in the classifier tank is above the spillway 43. The water from the classifier tank and from the pipes 9 travels up in the direction indicated by the arrows carrying with it the lighter material, which material is discharged with the water through the spillway.

The operation is adjustable by adjusting vertically the height of the classifier tank by adjusting vertically with respect to the classifier tank the valve 45 and by controlling the rate of flow of the water through the pipes 9. The material light enough to be supported by the upward flowing current in the sorting column is discharged through the spillway; the heavier material is sorted out and de-watered and treated in the same way as shown in the device in Figures 1, 2 and 3.

In Figure 7, is shown the apparatus which embodies the de-watering device in connection with the vibrating screens. To classify the material, bin 51 is for fine gravel. Bin 52 is for medium gravel, and bin 53 for coarse gravel. Gravel to be classified and de-watered comes to the apparatus on a conveyer belt 54, discharges over the pulley 55 to a vibrating screen 56. The water is sprayed upon the screen and its burden is discharged through the perforated spray pipes 57. The oversize is discharged from the screen into the coarse gravel bin 53. The undersize is discharged to the de-watering trough 58, of the kind disclosed in Figures 1, 2 and 3. This material is conveyed upwardly by the de-watering belt 59, discharged over pulley 60 to a screen 61 associated with the water pipes 62. The oversize returns to bin 52. The undersize goes to a second de-watering trough 63, being carried upwardly by the belt 64, discharged over the pulley 65, carried over the screen 66, and water at 67. The oversize on the screen 66 goes to the bin 51. The undersize, which in this case would

preferably be sand, would be fed to and treated by a third de-watering trough 68.

In the modified form shown in Figure 8, the apparatus in this case is supported upon a dredge scow or barge 80. The de-watering tank 81 is adapted to receive material excavated by the barge, and to be carried upwardly on and discharged by the de-watering conveyer belt 82. This belt is endless and travels around the pulleys 83, 84 at each end of the trough and is driven by two drive pulleys 85, and 86. The means for driving them is not here shown. The apparatus is so constructed that the travel of the belt may be reversed, and the belt may travel through the tank as indicated in Figure 8, so that material is discharged over pulley 83 to fill the scow 87. However, the drive movement may be reversed so that it will discharge over pulley 84 to fill the empty scow 88. Under these circumstances, space is not an important factor and the two sides of the drive system merely operates so that each one operates to de-water equally well.

Because the drive is applied to the ingoing end 25 of the belt, as in Figure 1, the tension side is outside of the tank. As a result the belt feeds smoothly and easily along the floor of the tank and no idler pulleys or guide means other than the supporting rails 8 are needed within the tank. Thus the problem of protecting bearings from 30 abrasions in the tank does not exist.

For the purpose of convenience and to avoid complication I have illustrated in Figure 7 the device of Figures 1, 2 and 3 thereof. Obviously 35 the device of Figures 4, 5 and 6 might equally well be used.

With reference to the device of Figure 7, it will be noted that in each case of the tanks 58, 63 and 68, only a relatively small amount of water is 40 used. The gravel or other material brought up by the conveyer 54 is discharged on the screen 56 which is illustrated as a vibrating screen but may be any suitable separating device and the flowing sheet of material passing down that 45 screen is washed by the spray. The spray water passes through the screen with the fines into the tank 58 and only enough water is discharged from the tank through the discharge opening 29 if the device of Figure 1 is used or through the 50 discharge opening 43 if the device of Figure 6 is used to compensate for the water added by the spray. Whatever dirt is washed off the sand or gravel is thus rapidly withdrawn from the system by the outflow of liquid only.

53 The material deposited in the tank 58 is then discharged by the conveyer 59 in what is at least a partially washed condition through the screen 61 to the tank 63, where it is again washed and the same thing happens with respect to the tank 68, thus the finer the material and the harder it 60 is to wash, the more washings it gets and the dirt washed off in each tank is withdrawn from the system, as distinguished from many types of apparatus hitherto known where the wash water travels through the entire system before being discharged, obviously better washing results because in each tank the washing is accomplished by fresh, clean water.

When the device of Figures 4, 5 and 6 is used 70 in such an assembly as that disclosed in Figure 7, true classification takes place because each tank and screen assembly discharges three products, the screen takes out the oversize, the sorting column takes out the undersize and the belt discharges the intermediate size—the great bulk of 75

the material—to the next stage in the process, thus a very accurate separation takes place and correct and accurate classification is possible.

One way in which my apparatus is adapted to be used to classify sand is by using a plurality of devices such as those illustrated in Figures 4, 5 and 6 in series. Sand is fed to the first one, the heavy sand passes out on the belt as a finished product. The lighter sand and water discharging through the chutes 43 will be supplied to the next classifier in the series. The supporting effect of the hydraulic classifying column traveling upwardly between the walls 42 and 44 will be reduced either by reducing the liquid velocity or by changing the distance between the walls, or both, so that the heavier sand in the remaining mass of material will be settled out and carried off on the belt as a finished product, the sand and water passing up through the classifying column will then be discharged as a finished product or subjected to a treatment in a third classifier.

Attention is especially called to the fact that the belt upon which the material is supported and by which it is propelled is a belt in the strict sense of the word as differentiated from chains, flight conveyers, screw conveyers and the like. It is essential as experience shows in connection with this device that the belt itself move with the material, that the material be spread in a relatively thin uniform layer upon, be supported by, and carried by the belt. The reason for this is that if a flight conveyor or anything of that kind is used, the material piles up in front of the flights in a series of separate masses which do not readily drain so that if an attempt is made to accomplish the same purpose with a flight conveyor, degradation of the material results and the material is not effectively dewatered. Moreover since each flight of a flight conveyor serves as a dam the water draining out must travel around the ends of the dam which causes agitation, cavitation and decreased efficiency.

I claim:

1. The method of treating comminuted solids which consists in depositing them in a liquid containing feed zone, controllably discharging them therefrom into a liquid containing classification zone, there subjecting them to the classifying effect of an upwardly traveling liquid stream, discharging said stream with entrained solids from the system, distributing the solids not entrained by the stream in a relatively thin, narrow sheet and conveying such sheet upwardly along a gradually inclined path emerging from and extending above the liquid level of the classification zone, the velocity of travel being such that agitation of the liquid is substantially prevented, the path extending upwardly above the liquid level for a distance sufficient to permit entrained liquid to flow out of and escape from the sheet of solids and then discharging the de-watered solids continuously from the system.

2. A de-watering trough having an inclined floor extending upwardly above the level of the liquid contained therein, a conveyer belt, means for propelling it upwardly along the floor, means for supplying material to the trough and distributing it in a sheet upon the belt, and means for discharging the de-watered material from the belt, and means for introducing liquid under pressure to the trough beneath the belt and means for discharging the liquid from the trough at a point above and far removed from the belt.

3. A de-watering trough having an inclined

floor extending upwardly above the level of the liquid contained therein, a conveyer belt, means for propelling it upwardly along the floor, means for supplying material to the trough and distributing it in a sheet upon the belt, and means for discharging the de-watered material from the belt, spaced wear strips on the floor of the tank adapted to support the belt, and means for introducing liquid under pressure beneath the belt into the space between the wear strips and means for discharging the liquid from the trough at a point above and far removed from the belt.

4. A de-watering trough having an inclined floor extending upwardly above the level of the liquid contained therein, a conveyer belt, means for propelling it upwardly along the floor, means for supplying material to the trough and distributing it in a sheet upon the belt, and means for discharging the de-watered material from the belt, the supplying and distributing means including downwardly and inwardly inclined guide members terminating adjacent but out of contact with the belt, the distance between the members increasing in the direction of travel of the belt.

5. In combination a de-watering trough adapted to contain liquid, means for maintaining the liquid level, thereof, a discharge tank contained within the trough having a discharge below the level of the liquid in the trough and means for maintaining the liquid level in the tank above the level of the liquid in the trough, means for supplying material to be treated to the tank, means adapted to control the rate of flow of material from the tank to the trough, means for supplying liquid under pressure to the trough and for guiding said liquid in an ascending current past the point of discharge of the tank upwardly to a discharge from the trough, means associated therewith for distributing the material in the trough, the trough having an upwardly inclined floor beneath said distributing means, a conveyer belt adapted to travel along said floor, along a path inclined upwardly from a point below the level of the liquid in the trough to a point above such level, means for discharging entrained material from the belt at a point above the level of the liquid in the trough.

6. In combination a trough having a floor including two outwardly and upwardly inclined elements, spaced wear strips projecting upwardly from the floor, a conveyer belt and means for propelling it along the floor of the trough along the wear strips, means for supplying material to the trough and guiding and distributing it upon the belt, a discharge pulley at one end of the floor of the trough over which the belt travels, means for forcing water under pressure into the spaces beneath the belt and adjacent the wear strips and means for discharging the liquid from the trough at a point above and far removed from the belt.

7. In combination, a liquid containing trough, having an inclined floor extending upwardly above the liquid level, a discharge pulley adjacent and tangent to the edge of the floor, a belt, means for propelling it along the floor towards and about the pulley, means for supplying comminuted solids and distributing them in a sheet upon the belt and causing them to travel upwardly along the floor over the pulley and to be discharged thereabout, wear plates on the floor supporting the belt, means for supplying liquid under pressure to the space between the floor and the belt to prevent deposit of solids therebetween and means for discharging the liquid

from the trough at a point above and far removed from the belt.

8. De-watering means including a tank having an upwardly inclined floor, means for maintaining a body of liquid in the tank, the liquid level intersecting the floor between its top and bottom, a belt and means for propelling it along the floor to emergence above the liquid level, skirt boards within the tank extending downwardly toward and terminating on a line generally parallel with the belt, the space between the boards increasing in the direction of travel of the belt, means for supplying water to the space beneath the belt and guiding it inwardly across the edge of the belt to prevent excessive discharge of solid material beyond the edges of the belt.

9. A material classifying device including a tank having oppositely inclined walls, a second tank therein having outwardly inclined walls generally parallel with the walls of the first named tanks, means for supplying liquid under pressure to the bottom of the first named tank to cause a flow upwardly through the space between the walls of both tanks, means for supplying material to be treated to the upper of the two tanks, means for controlling the rate of flow of the material from said tank into the second one and means for adjusting the size of the space between the walls of the two tanks.

10. A dewatering trough having a bottom comprising a relatively short and sharply inclined ramp, a relatively long and less sharply inclined ramp and a curved ramp joining and tangent to their lower ends, side walls being in liquid tight engagement with the edges of said ramps to form a tank, the longer ramp projecting above the upper edges of the walls, a guide chute in the tank masking the shorter ramp and terminating at its lower end above but adjacent to the curved ramp, means for discharging material to be treated upon the guide chute and causing it to slide downwardly therealong, a continuous endless conveyer belt, means for propelling it along and in contact with all three ramps throughout substantially their entire length, a discharge roller at the upper end of the long ramp over which the belt travels for discharge of material therefrom, walls extending upwardly along both sides of the longer ramp above the tank walls and means for controlling the level of the liquid in the tank.

11. A dewatering trough having a bottom comprising two inclined ramps extending upwardly and outwardly in opposite directions, a curved ramp joining and tangent to their lower ends, side walls in liquid tight engagement with the ramp to form the tank, one of the ramps extending outwardly and upwardly above the upper edges of the side walls, an endless belt adapted to travel along and in contact with all three ramps throughout substantially their entire lengths, means outside of the tank for propelling the belt, a roller at the upper end of the ramp and tangent to it about which the belt travels.

12. A dewatering trough having a bottom comprising two inclined ramps extending upwardly and outwardly in opposite directions, side walls in liquid tight engagement with the ramp to form the tank, one of the ramps extending outwardly and upwardly above the upper edges of the side walls, an endless belt adapted to travel along and in contact with the ramps throughout substantially their entire lengths, means outside of the tank for propelling the belt, a roller at the upper end of the ramp and tangent to it about which the belt travels, the belt propelling means being at the end of the tank opposite to the roller, the tight side of the belt extending outside the tank from the roller to the belt propelling means, the slack side of the belt being in the tank.

13. A dewatering trough having a bottom comprising two inclined ramps extending upwardly and outwardly in opposite directions, side walls in liquid tight engagement with the ramp to form the tank, one of the ramps extending outwardly and upwardly above the upper edges of the side walls, an endless belt adapted to travel along and in contact with the ramps throughout substantially their entire lengths, means outside of the tank for propelling the belt, a roller at the upper end of the ramp and tangent to it about which the belt travels, the belt propelling means being at the end of the tank opposite to the roller, the tight side of the belt extending outside the tank from the roller to the belt propelling means, the slack side of the belt being in the tank, means in the floor of the tank beneath the belt for introducing water under pressure and means at a point removed from the belt for discharging the water from the tank.
